UNITED STATES PATENT OFFICE.

JONATHAN AMORY AND WM. P. PARROTT, OF BOSTON, MASSACHUSETTS.

FURNACE OF STEAM-BOILERS.

Specification of Letters Patent No. 11,150, dated June 27, 1854.

To all whom it may concern:

Be it known that we, JONATHAN AMORY and WILLIAM P. PARROTT, both of Boston, in the county of Suffolk and State of Massachusetts, have invented certain new and useful Improvements in Locomotive and Steam Boiler Furnaces, &c., and that the following description, taken in connection with the accompanying drawings, hereinafter referred to, forms a full and exact specification of the same, wherein we have set forth the nature and principles of our said improvements, by which our invention may be distinguished from others of a similar class, together with such parts as we claim and desire to have secured to us by Letters Patent.

The figures of the accompanying plate of drawings represent our improvements.

Figure 1 is a central longitudinal vertical section of a locomotive boiler, with our improvements applied thereto. Fig. 2 is a transverse vertical section of the same taken in the plane of the line AB. Fig. 3 is a transverse vertical section taken in the plane of the line CD.

Our improvements are designed for the purpose of effecting a saving in the quantity of fuel consumed in heating locomotive, marine, and other steam boilers, and are more particularly applicable to "Baker's steam boiler furnaces" so called. This desideratum of economizing the fuel is effected by supplying the fire chamber with hot air, instead of cold air, thereby rendering the combustion of fuel more uniform and perfect. In "Baker's furnace," as is well known, the unconsumed gases, and other volatile products, which emanate from the fuel, are retarded in their passage to the chimney or delivering flue, by a series of reverberatory chambers, of semi-elliptical form, leading from the fire place, through which the said products are circulated and retained long enough to exhaust their heat, deliver the same to the boiler, and insure their perfect combustion, before they are permitted to escape. The passages or chambers under the boiler are thus kept constantly heated, and it is by taking advantage of this circumstance, that we are enabled to convey hot air instead of cold air to the burning fuel.

We have also made an essential improvement by which the carbonic acid gas, or other heavy and incombustible gases, can be conducted out of the furnace. The presence

of carbonic acid gas, in furnaces, and especially in locomotive boilers, has hitherto proved a serious objection, as it is incombustible, and retards the combustion of the other products. We effect this desideratum of conducting off the carbonic acid gas, by inserting a pipe which communicates, at one end, with the bottom of the furnace, and at its other end, with the smoke flue or pipe.

a a in the drawings represents a locomotive steam boiler, surrounding and incasing a furnace constructed on the principle of "Baker's furnace."

b b is the fire chamber.

d, d &c. are a series of reverberatory chambers, of a curved or semi-elliptical form, communicating with the fire chamber *b b*, and formed by the fire bridges *e, e* &c. In a stationary engine these chambers *d, d &c.* may also communicate by means of the spaces *f, f* with a series of ovens *g, g* under the fire bridges *e, e*. The smoke, gases and other volatile products which escape from the fuel, pass from the fire chamber through the throats formed between each fire bridge and the bottom of the boiler, into the chambers *d, d*, and by the form of these chambers, are made to revolve and circulate in the same, till they are entirely consumed, and their heat delivered to the boiler. Thus it will be seen that the chambers *d, d*, and the spaces *f, f*, are kept constantly hot. In order to make use of this heat, we insert near the bottom of the furnace, and through the fire bridges *e, e*, a pipe or tube *h h*, one end of which enters into the fire chamber *b b*, while the other end communicates with the cold external air. The cold air, which thus enters the pipe *h h*, becomes gradually heated, by passing through the said pipe, which is kept hot by the circulation of the heated currents in the chambers *d, d*—spaces *f, f &c.*, and passes directly into the fire chamber, thus supplying hot air to the said fire chamber, and insuring a more perfect combustion, and consequently requiring less fuel, as will readily be understood without further suggestion.

It will be seen from the foregoing description that the pipe *h h* is kept hot, not by applying to it heat produced by extraneous means, but simply by the heat already produced in the ovens or chambers, from the main fire chamber, and that consequently, hot air is supplied to the fuel, in an exceed-

ingly simple and efficacious manner, while the pipe h and the air which enters the same, gradually increases in heat as it approaches the fire chamber.

- 5 The pipe h instead of entering into the fire chamber as shown in the drawings, may extend no farther than into any one of the reverberatory chambers d , d , as it will thus supply hot air to the said chambers, and 10 facilitate the combustion of the volatile products in the same, and it will further be evident that instead of one conducting pipe h any desired number can be used.

The second part of our invention, by 15 which the heavy and incombustible gases are conducted off, consists in inserting a pipe i at the end of the furnace most remote from the fire chamber, and placed near the bottom of the furnace. The other end of the 20 pipe i communicates with the smoke pipe k . The carbonic acid gas, or other heavy and incombustible gases, which retard the combustion of the more volatile products, will be carried along by the heated currents 25 passing through the chambers d , d , and being heavy, will fall, when arriving at the end of the furnace, near to the bottom of the same, and will escape through the pipe i into the smoke pipe. The pipe i is 30 represented in the drawings, as being of larger diameter than the pipe h , and the latter pipe as passing through the pipe i , but it will be evident that the two pipes may be arranged entirely independent of each other, but the 35 former mode is preferable as the external

pipe i , i , acting as a jacket, surrounds the pipe h , h , with the heated incombustible gases, in their outward passage; whereby an important addition of heat is secured to the air passing through the pipe h , h , which 40 would otherwise be wasted.

The ovens under the fire bridges may be constructed in such a manner as to contain water and be connected to, and make part of the steam boiler, or to contain heated air, 45 as the nature of the work or the fuel of the engine requires.

Having thus described our improvements we shall state our claims as follows.

What we claim as our invention and desire to have secured to us by Letters Patent is—

1. Conducting off the carbonic acid gas, or other heavy and incombustible gases which check combustion, by means of a pipe 55 which communicates with the bottom of the furnace at or near one end of the same, and with the smoke pipe or flue as above described.

2. We claim, including a portion of the 60 air pipe h , h , within a larger pipe or jacket i , i , through which the heated and incombustible gases pass, in their exit from the furnace, substantially as described and for the purposes specified.

JONATHAN AMORY.
WM. P. PARROTT.
